[57] **CLAIM**

The ornamental design for an ejector holder for a syringe-type cartridge, as shown and described.

DESCRIPTION

FIG. 1 is a front elevational view of an ejector holder for a syringe-type cartridge embodying our new design;

FIG. 2 is a rear elevational view of the ejector holder shown in FIG. 1;

FIG. 3 is an elevational view of the right side of the ejector holder shown in FIGS. 1 and 2 and is a mirror image of the left side thereof;

FIG. 4 is a top plan view side of the ejector holder shown in FIGS. 1 to 3; and,

FIG. 5 is a bottom plan view side of the ejector holder shown in FIGS. 1 to 4.
